UNITED STATES PATENT OFFICE.

SIDNEY H. SHORT, OF COLUMBUS, OHIO.

SWITCH MECHANISM FOR ELECTRIC RAILWAYS.

SPECIFICATION forming part of Letters Patent No. 398,663, dated February 26, 1889.

Application filed November 13, 1888. Serial No. 290,762. (No model.)

To all whom it may concern:

Be it known that I, SIDNEY H. SHORT, of Columbus, in the county of Franklin and State of Ohio, have invented a new and useful Improvement in Switch Mechanism for Electric Railways; and I do hereby declare that the following is a full, clear, and exact description of the same.

The invention which is the subject of the following specification consists of an improved switch mechanism designed for a double-lined sectional conductor, such as that shown in Letters Patent of the United States granted to me the 4th day of December, 1888, No. 15 394,139.

I have sought to provide a switch mechanism adapted to prevent sparking and to be operated with certainty when the cars are running at a high rate of speed.

20 The particular improvements consist in combining with the double-line sectional conductor a switch arranged to open and close alternately the sections of the double line, and a trolley adapted to provide a short circuit between the lines at the break and around the switch during the shifting of the said switch to close one and open the other, whereby all sparking is prevented.

25 The invention further consists in a locking device in connection with the switch, whereby its action is rendered certain however high the rate of speed of the trolley.

30 Further, the invention consists of important combinations and details of construction.

35 In the accompanying drawings, which illustrate my invention, Figure 1 represents the conductor, trolley, and switch in side elevation. Fig. 2 represents an end view of the 40 switch, but on a scale larger than Fig. 1. Fig. 3 shows a side elevation of the switch, and Fig. 4 a plan of the same, both on the same scale; and Fig. 5 shows the commutator-sleeve detached. Fig. 6 shows the trolley in plan. Fig. 45 7 is a diagram of the switch, showing the trolley and the relation of the same to the operating-levers, whereby the switch is short-circuited as the trolley passes it.

In the drawings, A and A' represent the 50 sections of wire of a double conductor of an electrical railway. The sections of each wire

of the double line are continuous. The ends of the sections of each wire of the line are mechanically connected each to a plate, B, the lower edge of which is grooved to receive it. 55 To make a firm mechanical as well as a good electrical connection the end of the wire is turned up and driven into a hole in the under edge of the plate, and then the wire is soldered in the plate. At each break there are four 60 of these plates, two on each side. They are all supported upon a frame, D, having flanges d, which project downward. On each flange two plates are fixed by means of screws 1, which pass through the plates and into the 65 flange. An insulating-plate, E, is interposed between the plates and the flange, by which every plate is entirely insulated, and those of the pairs on each side are separated far enough to make an effective break in the 70 line.

Upon the frame in central longitudinal line is a shaft, F, which turns in bearings in standards f on the frame. On the ends of this shaft are fixed commutators G G', each 75 having two conducting-sections set opposite each other and two non-conducting sections similarly arranged; but the non-conducting sections of one commutator are opposite the conducting-sections of the other. Spring- 80 brushes 2, 3, 4, and 5, one on each side of each commutator, are insulated in supports on the frame.

In Fig. 4 of the drawings the car is supposed to be moving from left to right. The 85 brushes 2 and 3 of the left-hand commutator are connected, respectively, by wires 8 and 9 to the plates B of the right-hand wire, and when these brushes bear upon the non-conducting sections the connection is broken in 90 this wire, and when they bear on the conducting-sections the connection is closed. In the same way the plates on the other side are connected by wires 10 and 11, respectively, to the brushes of the commutator on the other 95 end of the shaft, but owing to the alternate arrangement of the conducting and non-conducting sections of the commutators in relation to each other, as heretofore described, when one connection in either wire is broken 100 the other is closed. The conducting-sections and their intermediate connections are made

out of a tubular piece of metal, II, as shown in Fig. 5, in which parts are cut out, as shown at *h*, leaving a ring, I, at the ends to form the connection. The parts cut out are filled with 5 any suitable non-conducting material. To give the shaft which carries these commutators the proper rotary movement to open on one side of the line and close on the other, I have provided mechanism worked by the passage 10 of the trolley. First, there is a star-wheel, K, fixed on the shaft of the commutators with its radii in proper relation to the sections of the commutator. To move this step by step and to lock it in position when moved, arms 15 L and M are provided. These are conveniently in one piece, being pivoted at 14 on one side of the frame. The moving arm L is shorter and has a spur, *l*, which normally stands in position, as shown in Fig. 2, to strike 20 a radius of the star-wheel and move it one step. While it is so moving the other arm, M, being longer, moves faster and downward and, leaving the opposite radius, unlocks the wheel.

This locking-arm has an enlarged bearing-face adapted to the face of the wheel against which it bears. As the locking-arm moves backward and downward the moving arm carries the wheel nearly one-fourth of a revolution and there holds it until the force which 30 moved the arms has ceased to act. Then the arms are returned to their normal position by means of a spring, N, which bears against the under side of the long arm. This carries the long arm up against the next radius, completing 35 the one-fourth movement heretofore explained, and moving the radius-point on the other side to the position shown in Fig. 2, when it stands ready to be engaged again by the moving arm.

40 The arms L and M are operated directly by means of levers O and P. These are pivoted on the plates B B and are in electrical connection with said plates. The lower ends extend down and have friction-rollers in range 45 of the passing trolley. The upper ends extend inwardly over insulating-sleeves *p* on a pin inserted through the long arm M. Two levers are used, so as to equalize the strain on the trolley and prevent its displacement and 50 to make electrical contact with the trolley to prevent sparking. When the trolley passes between the lower ends of the levers, it pushes them outwardly and the inner ends down, thus depressing the long arm M and throwing inwardly the short arm, with the effect hereinbefore described.

Supposing the trolley to be advancing, therefore, from left to right, as in the diagrammatic view, Fig. 7, and the right-hand wire of the 60 line to be closed in front of it, while the left is open in front, the conditions being reversed in rear, the trolley, in the manner described, gives a quarter-turn to the commutators and reverses the switches, opening the right and 65 closing the left, and as the trolley moves on the current continues to pass from the right-hand wire through the motor and on to the

left-hand line, as more fully explained in my said application.

In order to prevent the formation of an arc 70 in the interval of shifting the switch, I have made provision which relates partly to the construction of the trolley, and is illustrated in Fig. 6 of the drawings. It will be understood that the trolley Q is carried on a yielding arm, R, upheld by springs *r r*, and bears 75 against the under side of the wires. It has two contact-wheels, each in connection with one terminal of the motor. Outside these wheels and in electrical connection therewith are two curved contact-pieces, which bear 80 upon contact surfaces or rollers on the lever and push out the levers and also put them in electrical connection with the trolley-wheels so long as the contact-pieces bear thereon. 85 These levers are electrically connected to their supporting-plates, and these plates, as before stated, are electrically connected with the conductors. Referring to Fig. 7, it will be noticed that the wings of the trolley extend 90 forward some distance beyond the point of contact between the trolley and the conductor, which point, of course, is in the same vertical plane with the axle. The trolley is moving from left to right, the right-hand conductor 95 is closed, and the opposite conductor is open. The ends only of the lever are shown at O P. As soon as the forward-projecting ends of the trolley-wings strike the levers, an electrical short circuit will be formed as follows: 100 through the trolley-wheel on the left-hand conductor, the motor, the wing of the trolley, which is on the right-hand conductor, thence through the lever on that side, and to the conductor. This circuit is independent of the 105 switch, and is in action during the shifting of said switch. The contact of the wings with the lever not only establishes this circuit, but causes the operation of the switch, as already described, and the circuit is maintained until 110 the trolley reaches the space between the conductor-sections, at which time the operation of the switch has been completed. The connection of the line with the motor is constant, and no arc can be formed on either side. 115

I claim as my invention—

1. In combination with a sectional double line-conductor of an electric railway, a switch between the sections adapted to open one line and close the other upon the passage of the 120 trolley, and a trolley having connection with both lines and arranged to operate the switch in its passage, and having also contact-surfaces in connection with the terminals of the motor, contact-surfaces in connection with 125 the conductors and in line with the contact-surfaces of the trolley arranged to short-circuit the switch and establish an electrical connection between the conductors while the switch is shifting, substantially as described. 130

2. In combination with a double sectional line-conductor of an electric railway, a switch located between the sections, electrical connections between the sections of each line

through a commutator, and a lever for operating the commutators, a trolley having contact-surfaces in line with the lever, whereby said lever is operated by the passing trolley 5 and one line is closed and the other opened by the passage of the trolley.

3. In combination with a double sectional line-conductor of an electric railway, a supporting-frame, plates attached to the sides 10 thereof, and interposed insulating-pieces, said plates having the ends of the sections attached thereto, two commutators mounted on the frame, each commutator being interposed between the sections of one of the lines, and 15 levers arranged to turn the commutators upon the passage of the trolley, substantially as described.

4. In combination with a trolley, a supporting-frame, the insulating-plates B B', to which 20 the ends of the sections are attached, the shaft carrying two commutators supported in standards on the frame, each commutator having two conducting and two non-conducting sections arranged alternately in respect 25 to each other, connections between the sections on each line through one of the commutators, and mechanism in the path of the trolley for turning the commutators one-fourth revolution by the passage of the trolley, sub- 30 stantially as described.

5. In connection with the commutator-shaft arranged upon the frame and in the described relation to the sections of the line, a star-wheel on the shaft, the operating and locking 35 arms for the star-wheel, a lever arranged to

operate these arms having its lower end in range with the trolley and adapted to be operated thereby, and means for returning the arms after the trolley has passed, substantially as described.

6. In combination with the star-wheel of the commutator-shaft, the short arm L and the long arm M, pivoted to move together, an insulating-bearing on the long arm for the operating-lever, the said operating-lever being pivoted upon the side plate, having its upper end arranged to bear upon the insulating-bearing of the long arm and its lower end extended into range with the trolley, and the spring for returning the arms L and M, sub- 40 45 50 stantially as described.

7. In combination with the arms operating with the commutator to ship the switch, said arms being in electrical connection with the line-sections on one side of the break, a trolley 55 having contact-surfaces for the levers in electrical connection with the terminals of the motor, and arranged to short-circuit the switch and establish an electrical connection between the sections on the passage of the 60 trolley and while the switch is shifting, all substantially as described.

In testimony whereof I have signed my name to this specification in the presence of two subscribing witnesses.
